Primary Examiner — Mary Ann Calabrese(74) Attorney, Agent, or Firm — Cantor Colburn LLP(57) CLAIM

We claim, the ornamental design for a typeface, as shown and described.

DESCRIPTION

FIG. 1 is a face view of a typeface showing my new design; FIG. 2 is a face view showing the letters in use, the words shown form no part of the claimed design; and, FIG. 3 is an enlarged face view of a represented sample of characters.

The broken lines form no part of the claimed design.

1 Claim, 3 Drawing SheetsFIG. 1

ABCDEFGHIJKLMNOPQRSTUVWXYZ

FIG. 2

The quick brown fox jumped over the lazy dog

The quick brown fox jumped over the lazy dog
